UNITED STATES PATENT OFFICE

171,385

GASOLINE MOTOR HOUSING

Charles W. Butler, Englewood, N. J., assignor to
Toro Manufacturing Corporation of Minnesota,
Minneapolis, Minn., a corporation of Minnesota

Application August 7, 1953, Serial No. 26,342

Term of patent 14 years

(Cl. D40—1)

To all whom it may concern:

Be it known that I, Charles W. Butler, a citizen of the United States of America, residing at Englewood, county of Bergen, New Jersey, have invented a new, original, and ornamental Design for a Gasoline Motor Housing, of which the following is a specification, reference being made to the accompanying drawings, forming a part hereof, and in which:

Fig. 1 is a perspective view of a gasoline motor housing showing my new design;

Fig. 2 is a plan view of the housing;

Fig. 3 is a side elevational view of the same;

Fig. 4 is a front elevational view of the housing; and

Fig. 5 is a rear elevational view of the same.

I claim:

The ornamental design for a gasoline motor housing, substantially as shown.

CHARLES W. BUTLER.
